ATTORNEY.

UNITED STATES PATENT OFFICE.

KENNETH BELDIN, OF GLENDALE, CALIFORNIA.

ILLUMINATED HOUSE NUMBER.

Application filed July 14, 1926. Serial No. 122,384.

My invention relates to electrically illuminated signs and more particularly to an electrically illuminated house number.

In all illuminable house numbers on the market other than mine, the lamps thereof are wired with rubber-covered 110 volt wire which is required by law to be run to the box of the house number, through a pipe conduit. This makes the installation of the ordinary 10 illuminated house number an expensive feature of house building. In case the illuminated house number is installed after the house has been built, the cost is so great, that while these numbers have been on the market 15 many years and while they are very desirable to have to inform persons of the location of the house at night, the sale of such numbers has been very small. Although the lamps drawing the lowest amperage possible from 20 the 110 volt circuits may be used in these old illuminable house numbers even this low candle-power lamp, burning at night, causes considerable heat in the box of the house number and uses up sufficient current to cost for 25 maintenance between three and four dollars a month for burning the lamp only during the dark hours of the day. An additional installation expense is also necessary to provide a conduit box and a wall switch where- 30 by the circuit of the house number lamp could be turned on each evening and turned off the following morning. The daily turning on and off of this switch requires the attention of the house owner and in a majority of cases, 35 the switch is neglected, causing the number to be dark at night or else doubling its excessive maintenance cost by burning the lamp through the daylight hours. It is a broad object of my invention to provide an 40 illuminated house number having a low voltage circuit and a low voltage lamp associated with a constant source of electricity at low voltage.

The above feature permits the illuminated house number of my invention to be installed 45 at a very low cost and to be kept lighted twenty-four hours a day at a small fraction of the maintenance expense incidental to the use, during the dark hours, of the old house 50 numbers illuminated by the 110 volt circuit.

In addition to saving the expense of installing the conduit, the box of the illuminable house number of my invention, being lighted by a low voltage circuit, may be made 55 of much lighter and therefore cheaper metal

than the heavy metal required by law in many States for metal boxes into which wires carrying 110 volts must pass.

It is another object of my invention to provide an electrically illuminated house number which is of an extremely simple structure comprising a small number of parts which may be cheaply formed and easily assembled, thus enabling an illuminated house number to be put on the market at a relatively low 65 price at considerable profit to the manufacturer.

Other objects and advantages of my invention are made manifest in the following description and accompanying drawing in 70 which:

Fig. 1 is a perspective view showing the illuminated house number of my invention applied to a wall of a dwelling in which the outer surface thereof is formed of wooden 75 siding.

Fig. 2 is a vertical sectional view taken on the line 2—2 of Fig. 1.

Fig. 3 is a horizontal sectional view taken on the line 3—3 of Fig. 2.

Fig. 4 is a perspective view illustrating the light receptacle clip of my invention.

Fig. 5 is a vertical sectional view of a modified form of my invention.

Fig. 6 is a horizontal sectional view taken on the line 6—6 of Fig. 5.

Fig. 7 is a perspective view illustrating the modified form of my invention, which is shown in Fig. 5, installed in a brick wall of a dwelling so that the outer face thereof lies 90 flush with the outer surface of the wall.

Fig. 8 is a perspective view illustrating the installation of the novel low voltage circuit of my invention.

Fig. 9 is a diagrammatic view illustrating 95 the low voltage electric circuit of my invention.

Fig. 10 is a front elevational view of the preferred form of the house number of my invention, parts thereof being broken away 100 so as to illustrate certain features.

Fig. 11 is a view similar to Fig. 2, illustrating the house number of my invention installed in a stucco wall.

Fig. 12 is a front view illustrating the 105 drain feature of the lower glass retaining lip of the light box structure of my invention.

Referring to the drawing in detail, 10 indicates the frame of a house having wooden siding 11 provided upon the outer surface 110

thereof. A door 12 is provided in the frame 10 as illustrated in Fig. 1. Outside of a jamb 13 of the door 12 is a hole 14 formed in the siding 11 in which the illuminated house 5 number 15 of my invention is inserted.

The house number 15 has a box like structure 16 in which a central member 19 is formed, entirely by bending, from a sheet of metal 20. The sheet 20 is rectangular, having 10 a horizontal dimension X, as shown in Fig. 3, and it is bent horizontally at 21 to form upper and lower diverging reflecting walls 22 and 23. The wall 22 is bent at its upper end to form a horizontal wall 24. At the 15 outer edge of the horizontal wall 24, the sheet 20 is bent downward and upward against itself to form an upper number-glass retaining lip 25. As the upper end of the lip 25 the sheet 20 is bent rearward so as to lie flush 20 against the upper surface of the wall 24 thus forming an upper horizontal wall 28. The wall 28 extends inward, as shown in Fig. 2, being bent upward at its inner edge to form 25 an upper attaching flange 30. The reflecting wall 23 inclines forward and downward, as shown best in Fig. 2, to a point directly below the outer edge of the upper horizontal wall 24. Here the sheet 20 is bent upward a given distance and then downward upon its 30 self to form a lower glass retaining lip 33. The outer lower portion of the lip 33 of the sheet 20 is bent inward and upward to lie flush against the lower face of the reflecting wall 23 for a short distance from the lower 35 edge thereof. The sheet 20 is bent downwardly so as to form a lower connecting flange 35. Rectangular sheet metal ends 38 and 39 abut against opposite ends of the central member 19 which is formed entirely by bending the rectangular sheet 20 as above 40 described.

The forward edges of the sheet metal ends 38 and 39 are bent backward upon themselves to form outer retaining flanges 45 40 and 41 and then bent inward to form inner retaining flanges 42 and 43. The ends 38 and 39 are soldered to the central member 19 so that the outer retaining flanges 40 are disposed opposite the space directly behind the upper and lower retaining 50 lips 25 and 33 and so that the inner retaining flanges 42 and 43 are disposed rearward a given distance from the outer ends of the lips 25 and 33.

55 A light receptacle clip 44 which is best illustrated in Fig. 4 is formed of a single strip of metal 45 of uniform width which is bent upon itself centrally at 46 so that opposite halves 47 and 48 thereof lie flush against 60 each other. Both of the halves 47 and 48 are bent at 49 to provide a securing lug 50 adjacent to the bend 46 and an arm 52 which is formed by the free ends of the halves 47 and 48. The extreme end portions of the 65 halves 47 and 48 are formed outward to pro-

vide arcuate opposed retaining members 53 and 54 adapted to securely grip a receptacle 55 which contains a light bulb 56. The securing lug 50 of the light receptacle clip 54 is soldered to the lower portion of the reflecting wall 22. The arm 52 projects horizontally outward into a light chamber 58 located between the upper and lower reflecting walls 22 and 23. Electricity is supplied to the light bulb 56 through the receptacle 55 by means of insulated wires 60 which lead from the receptacle 55 through a hole 61 formed in the lower reflecting wall 23, to a suitable source of electricity (not shown).

A rectangular number-glass plate 65 is 80 adapted to be inserted into a rectangular opening 66 in the front of the box 16 which is bounded upon its upper and lower edges by lips 25 and 33 and upon its side edges by flanges 40 and 41. The glass 65 is of the 85 width, as indicated in Fig. 3, such as to permit it to be disposed between the side flanges 40 and 41. In order to place the glass 65 in the opening 66 it is first disposed in the position indicated by the dotted line 67 in Fig. 2 90 in which the upper edge of the glass 65 is inserted between the upper lip 25 and the inner flanges 42 and 43. The lower end of the glass 65 may then be swung inward over the upper edge of the lip 33 and allowed to drop downward between this lip and the inner retaining flanges 42 and 43. The upper edge of the glass 65 is then disposed above the lower edge of the lip 25 so as to be hid by this lip. The rear face of the glass 65 is provided with 100 decalcomania numbers in which the surfaces of the numbers are translucent and the surface surrounding the numbers is opaque.

In mounting the house number 15 in place, as shown in Fig. 1, the hole 14 is provided 105 in the wooden siding 11 so that the body or box structure 16 of the illuminated house number 15 may be disposed therein, as shown in Fig. 2. The upper and lower attaching flanges 30 and 35 are then in contact with 110 the siding 11 bordering the upper and lower portions of the hole 14 and are secured thereto by screws 70.

The box structure 16 of the illuminated house number 15 is formed of four pieces of 115 metal. These are the rectangular body-forming-sheet 20, the two rectangular ends 38 and 39, and the strip 45 which is used to form the light receptacle clip 44. Inasmuch as all these pieces of metal are rectangular 120 in shape, there is no loss of metal when these pieces are cut from larger sheets. Moreover, the dies by which these parts are formed are very simple and cheap in construction and may be operated at a high speed.

The clip 44 is of novel construction inasmuch as the arm 52 is formed of free end portions of the opposite halves 47 and 48 of the metallic strip 45. The arcuate end portions 53 and 54 of the half portions 47 and 48 130

therefore grip the receptacle 55 with a resilient pressure which tends to retain this receptacle 55 firmly in place.

In case it is desired to install the illuminated house number 15 in a stucco wall, the hole 14 is formed in the lathing upon which the stucco is to be applied. The flanges 30 and 35 are then secured (in the manner shown) to the lathing above and below the hole 14. When the stucco is plastered upon the lathing it may be of such thickness so that its outer surface will be substantially flush with the front face of the body 16. The flanges 30 and 35 will then be disposed between the lathing and the stucco and in addition to being secured to the lath by the screws 70, they will be gripped by the stucco and the laths and thus be secured rigidly in position.

A modified form of illuminated house number 79 is shown in Fig. 5. Here a peripheral wall 80, forming upper and lower walls 81 and 82 and end walls 83, is made from a single rectangular piece of metal, the opposite ends of which are soldered together at a corner of the peripheral wall 80. At the rear edges of the peripheral wall 80 an abutting flange 84 is formed inward for the purpose of strengthening the wall 80 and providing an abutment to rest against a wall 86 against which it might be desired to mount the house number 79. The end walls 83 of the peripheral wall 80 form the sides of a light chamber 88. A single rectangular sheet 90 is bent at 91 to form upper and lower diverging reflecting walls 92 and 93. The upper reflecting wall 92 is bent to form a horizontal wall 94 which lies flush against the inner surface of the upper wall 81 at the forward edge thereof. At the forward edge of the horizontal wall 94 the sheet 90 is bent downward and upward against itself to form an upper lip 95. The outer portion of the upper lip 95 extends upward, being bent inward to form a flange 96 which lies flush against the upper face of the forward edge of the upper wall 81. The lower reflecting wall 93 extends forward and downward to its lower edge, where it is bent upward and downward against itself to form a lower lip 98 which is disposed directly beneath the lip 95. The outer portion of the lip 98 extends rearward so as to form a flange 98a which lies flush against the lower face of the lower wall 82 at its forward edge. The reflecting walls 92 and 93 are soldered to the peripheral wall 80 when positioned as shown in Fig. 5. Thus the walls 92 and 93 co-operate with the end walls 83 to enclose the light chamber 88 which has a front opening 99 bounded at the top and bottom by the upper and lower lips 95 and 98 and at the sides by the front edges of the end walls 83. As shown in Fig. 6, rear stop flanges 100 are provided, each of which has a vertical socket 101 formed integral

therewith at its outer edge which fits and is soldered to the front edge of one of the end walls 83. When thus secured the flanges 100 are disposed rearward a short distance behind the upper and lower lips 95 and 98. A 70 number glass 102 may be installed in the front opening 99 of the light chamber 88 in the same manner as the number glass 65 is installed in the illuminated house number 15.

The illuminated house number 79 may be 75 secured upon the outer surface of the wall 86 by means of flat head screws 106 which pass through holes in the metal sheet 90 at the apex 91, as best shown in Fig. 5. The modified form of illuminated house number 79 80 is built in the same size as common brick, such as is used in the formation of a wall of a dwelling, and may be installed in the outer face of such a wall during its construction in the place of one of the bricks. When thus installed it will present the appearance as illustrated in Fig. 7. The house number 79 is supplied with a light receptacle clip and illuminating means in the same manner as the preferred form 15, and therefore are not 90 shown in Figs. 5, 6 and 7 which illustrates the modified form of my illuminated house number.

As illustrated in Fig. 12, the lower lip 33 of the box structure 16 of the illuminated 95 house number 15 is bent upward a short distance outward from the forward edge of the side flanges 40 and 41. Thus a small opening 106 is provided at the bottom of the trough formed below the lower edge of the 100 number glass 65 between the lower lip 33 and the lower reflecting wall 23. This opening 106 is provided as a drain for water which collects upon the face of the number glass due to conditions of the weather and which 105 flows downward therefrom into the trough beneath the lower edge of the number glass 65.

As clearly shown in Fig. 10, the lower ends of the inner retaining flanges 42 and 43 are bent forward to form supporting lugs 108 110 and 109. These lugs are disposed above the bottom of the trough, which is located below the number glass 65, so that when the number glass 65 is dropped into place behind the lower lip 33 the glass will drop downward only a portion of the height of the lower lip 33. This will cause the upper edge 110 of the number glass 65 to be retained a fair distance above the lower edge of the upper glass retaining lip 25. The lugs 108 and 109 115 also support the number glass 65 so that a space 111 is provided beneath the number glass 65 along which water may course in order to reach the openings 106 formed at opposite ends of the lower lip 33.

In Fig. 11 the house number 15 of my invention is shown as it is installed in a stucco wall. Here the ends 38 and 39 are attached by nails 115 to the studding 116 so that the flanges 30 and 35 rest against the upper and 130

lower laths 117 and 118 which border the upper and lower edges, respectively, of a hole 120 formed in the lathing and nailed to the studding 116. The upper wail 28 now forms 5 a weather strip against which stucco 121 may be plastered to such a thickness that its outer surface will lie flush with the outer surface of the number glass 65. The stucco 121 is applied to the lathing on the sides and below the house number 15 to the same thickness as it is applied above the house number. 10

In Fig. 8, I have shown the perspective view of a bungalow in which parts thereof are broken away to illustrate the great economy effected in the wiring of the house number of my invention. In this view, 130 indicates a house through the exterior structure of which electricity, having a potential of approximately 110 volts, is conveyed by the conduit 131 to a fuse and switch-box 132. Wires 15 convey the electricity from the switch-box 132 through metallic tubular conduits 133 to the various lighting outlets 134, which are disposed at various convenient stations 20 throughout the house 130. For each of the outlets 134 a T 135 must be provided in the conduit 133 and a branch conduit 136 must be run from the T 135 downward through a wall 137 to a suitable point where the branch 25 conduit 136 terminates in a metallic box 138 upon the face of which a switch plate 139 is installed. It is required by law that each outlet be provided with the conduits and fixtures just described. In the old form of 30 house number, which has been in use prior to my invention, it is necessary to run a conduit 133 from the switch-box 132 the full length of the house 130 to illuminate a house number 15 which it was desired to install, as 35 indicated, in the front wall 140 of the house 130. In addition to this lighting conduit it was necessary to provide a switch outlet by which the light placed in the house number 15 might be turned on at night and turned off 40 in the morning.

In my invention I utilize a low voltage transformer 146, which supplies current through suitable wires 147 and 148 which lead to the switch-box 132 of the lighting circuit 45 of the house 130. The illuminated house number 15, of my invention, is shown diagrammatically in Fig. 9 with the lamp 56 thereof connected to low voltage wires 160 and 161 and to secondary terminals 162 and 55 163 of the transformer 146. There being no switch in the wires 160 and 161 the lamp 56 will be constantly illuminated by current drawn from the low voltage transformer 146.

The advantages of the low voltage circuit, 60 illustrated diagrammatically in Fig. 9, are graphically shown in the perspective view of Fig. 8. In this view it will be seen that instead of an expensive conduit 133 leading from the switch-box 132 to the light house 65 number 15 in the front of the house, I have

merely to install the inexpensive low voltage transformer 146 with a pair of low voltage annunciator wires 160 and 161 leading therefrom to the house number 15. These wires 160 and 161 may be tacked, as indicated, by the 70 tacks 165 upon a beam 166 of the understructure of the house 130. The low voltage wires 160 and 161 are formed of small gaged wire wrapped with paraffined cotton and are very inexpensive in first cost and in cost of installation. Thus, by the provision of an illuminated house number having a low voltage circuit, including a source of constant supply, I have removed the greatest obstacle to the 75 furnishing of illuminated house numbers to 80 the public at a low cost of installation and maintenance which is within the reach of the average income.

I claim as my invention:

1. An illuminated house number comprising: end walls; a central member formed with upper and lower diverging reflecting walls and adapted to cooperate with said end members to form a light box, providing a light chamber having an indicia plate mounting space; upper and lower plate retaining lips bent inwardly in front of said plate mounting space from upper and lower portions, of said reflecting walls respectively, of said central member, the forward edges of said end walls being disposed opposite the sides of said mounting space and being bent inwardly upon themselves; upper and lower securing flanges rebent from said plate retaining lips; flanges re-bent from said inbent edges of said end walls to lie behind said plate opening space; and an indicia plate adapted to be freely inserted into or removed from said opening space by virtue of the vertical dimension of said plate being less than that of said opening 100 space.

2. An illuminated house number comprising: end walls; a transverse reflector member shaped to cooperate with said end walls to form a light box, providing a light chamber having an indicia plate mounting space; upper and lower plate retaining lips bent inwardly in front of said plate mounting space from upper and lower portions, respectively, of said reflector member, the forward edges of said end walls being disposed opposite the sides of said mounting space; upper and lower securing flanges rebent from said plate retaining lips; side plate retaining lips formed inwardly from the forward portions of said end walls to lie behind said plate mounting space; and an indicia plate adapted to be removably disposed in said space and retained in place at the front by said upper and lower lips, at the rear by said side plate retaining lips, and at the ends by said end walls and said flanges being adapted to be secured to the house structure for supporting said house number thereon.

3. An illuminated house number comprising:

ing: end walls; a central member bent medially in horizontal plane to form upper and lower diverging reflecting walls providing an indicia plate mounting space, said upper reflecting wall being bent at its upper end to form a horizontal portion and having the outer edge of said horizontal portion bent downward and upward upon itself to form a lip and an upper attaching flange, said lower reflecting wall inclining forward and downward to a point below the outer edge of the horizontal portion of said upper reflecting wall and being bent upward and downward upon itself to form a lower lip, the outer lower end of said lip being bent inward and upward to lie flush against the lower surface of said lower reflecting wall and downwardly to form

a lower attaching flange, the forward edges of said end walls being disposed opposite the sides of said mounting space and being bent inwardly upon themselves; flanges rebent from said inbent edges of said end walls to lie behind said plate opening space; and an indicia plate adapted to be freely inserted into or removed from said opening space and said attaching flanges being provided with securing means for the attachment of said end walls and reflector member to the house structure.

In testimony whereof, I have hereunto set my hand at Los Angeles, California, this 8th day of July, 1926.

KENNETH BELDIN.
